SPINDLE FOR STRAND WRAPPING MACHINES

Samuel Rushton Walsh, Valley Falls, R. I., and Henry Berger Ahlberg, Attleboro, Mass., assignors to H & B American Machine Company, a corporation of Maine

Application December 19, 1939, Serial No. 310,000

12 Claims. (Cl. 57—18)

This invention relates in general to strand wrapping spindles and is directed more particularly to improvements in the spindle package holder construction employed with spindles of this class; and has for one of its objects the securing together of the demountable parts of the spindle assembly by frictional members for ready removal for flier or package changes.

Another object of the invention is the easy removal or the assembly of the serving tip member or bullet from its spindle carried by the upper bobbin flange for flier changes without the loosening or the tightening of any screw-threaded members.

Another object of the invention is the detachable frictional connection of the demountable serving tip member or bullet to the spindle of the upper demountable bobbin flange and also the detachable frictional connection of the main driving spindle blade with the upper bobbin flange.

Another object of the invention is the adjustable connection of the upper and lower bobbin flanges so as to permit the mounting between them of any of a number of packages of covering material having different axial lengths with center cop-tubes of the same diameter.

Another object of the invention is to provide a main rotatable spindle of fixed length on which may be supported any of a plurality of interchangeable yarn packages of the same cop diameter but of different heights or axial lengths, and coupling means which is of an adjustable character to connect the upper and lower flanges to maintain the serving tip member or bullet and its hollow spindle member vertically centered with respect to the main hollow spindle.

Another object of the invention is the detachable connecting of both the serving tip member or bullet to its spindle and the upper flange to its spindle by separate frictional coupling devices each of which is so arranged that the connection or the release of the members from their respective spindles may be readily effected by either a pull or a push in a direction to perform the desired result.

With these and other objects in view, the invention consists of certain novel features of construction, as will be more fully described, and particularly pointed out in the appended claims.

In the accompanying drawings:

Fig. 1 is a central longitudinal sectional view through a strand covering spindle embodying the present invention and showing one form of package of the covering material in operative position on the spindle;

Fig. 2 is a central longitudinal sectional view of a modified form of the invention showing a covering spindle on which is mounted a taller package of the covering material, and an adapter member extending between and connecting the two flanges 5 of the opposite ends of the package;

Fig. 3 is a central sectional view, partly broken away, of another modification of covering spindle showing a different form of adapter structure and modified form of tip member;

Fig. 4 is a sectional view taken on the line 4—4 of Fig. 1 as viewed from the underside, and showing one form of demountable flange member for supporting the serving tip and the rotatable flier;

Fig. 5 is a central longitudinal sectional view of 15 a covering spindle, on smaller scale, illustrating a modified form of adapter device in accordance with the invention; and

Fig. 6 is a plan view of a flier for use with a covering spindle.

In the operation of strand covering spindles of this class, it is often desirable to employ strand covering materials of various sizes and weights for spirally covering the elastic strand material or core to be wrapped, which practice has necessitated any or all of the following steps, viz., the changing of either the size or the type of rotary flier used with such spindles, or of weighting the flier with a washer of the proper weight to cause the flier to impart the desired tensioning action 30 on the strand covering material being withdrawn from the supply package. The construction of one prior form of flange support for the flier and the guide member for the strand covering material in use at the present time has involved the disadvantage, however, of requiring the complete dismantling of the entire unit, piece by piece, by first removing the device from the center cop tube of the package of the covering material, and then unscrewing a short tubular-like nut from the end portion of the central tubular upright flier support passing through an annular flange to separate the parts before the removal and the replacement of the flier could be effected, which operation was expensive and time consuming in that it 35

not only required the use of tools, but it also necessitated stopping the entire machine for a long period with the consequent loss of productive time while such changes were being made to all the spindles; and in order to eliminate these prior 40 disadvantages, the present invention contemplates a spindle package holder construction which is so arranged that it may support any of a number of standard packages of covering material of different axial lengths but having the same size 45

50 55

of bore, the same length of spindle being used for supporting and driving all the various heights of packages; and there is further provided an upper bobbin flange which is demountable on the top 5 open end of the center cop tube of the various yarn packages, and a serving tip member or bullet which is demountable on the upright spindle member carried by such upper flange with frictional means holding the bullet to the spindle; 10 and there is further provided an adapter device between the main hollow driving spindle and the upper flange for connecting the same to the spindle to hold the flange and its bullet carrying spindle centered and in vertical alignment with 15 the main driving spindle blade when different sizes of the interchangeable packages of the covering material are employed and supported by the main driving spindle; and frictional means also is provided for detachably connecting the adapter 20 member to both the upper flange and to the main driving spindle, and the following is a more detailed description of the present embodiment of this invention, illustrating the preferred means by which these advantageous results may be accomplished:

With reference to the drawings, 10 generally designates one of a plurality of hollow covering spindles of a strand wrapping machine, preferably a rubber covering machine, in which the 30 spindles are of similar construction having a tubular base 11 which is cushioned to the usual horizontal spindle rail 12 by a suitable resilient material, such as a cork or rubber washer 13. To eliminate shock or vibration which may be caused by starting the spindle from rest to bring it up to its normal running speed and by the use of unbalanced packages of covering material thereon, the spindle is yieldingly held in place on the rail by means of the usual spring 14 which 40 encircles the depending tubular portion 15 of the base projecting through the rail, the spring 14 being interposed between the underside of the rail 12 and a nut (not shown) threadingly carried by the lower end portion of the tubular portion 15 of the base. In such machines, the spindles 10 are usually arranged in a staggered relation laterally of the rail 12 to form two longitudinal rows on the rail.

As illustrated in Fig. 1, the spindle is provided 50 with the usual hollow spindle blade 17 which is journaled in suitable anti-friction bearings (not shown) for rotation in the base 11 by means of the usual whorl 18 fast to the spindle blade and driven by a driving band 19, preferably a band or cord having an elastic structure, connected to any suitable source of power (not shown).

An idler whorl 20, which is loosely rotatable upon an upright tubular extension 21 integral with and rising upwardly from the base 11, is 60 provided below and close to the driving whorl 18 for temporarily receiving the revolving elastic band 19 in the event of breakage of the rubber core or of the strand covering material whereby the elastic driving band 19 may be readily shifted manually from the whorl 18 and slid 65 onto the idler whorl 20 in order to stop the spindle and enable the operator to piece up the break without stopping the rotation of the other spindles on the machine or that of the shifted 70 revolving band 19. A split ring or washer 22 located on the tubular extension 21 between the driving whorl 18 and the idler whorl 20 serves to separate and maintain the whorls in spaced 75 relationship at all times and prevent their adjacent end faces from rubbing against each other

so as to cause rotation of the spindle blade 17 when the revolving driving band 19 is temporarily shifted to an idling position on the idler whorl 20. The foregoing whorl structure is described and claimed in the copending application of Henry B. Ahlberg, No. 309,999, filed December 19, 1939, and "per se" it forms no feature of the present invention.

Disposed above the whorl 18 and carried by the spindle blade 17 is the usual package 25 of strand 10 covering material, usually consisting of some textile material in strand form, such as cotton, silk or rayon yarn, which package is held at both its ends between a pair of annular flanges 26 and 27, each of which has a plurality of prongs 28 15 and 29 respectively formed of some resilient material which are insertable within and wedgingly engage at diametrically opposite points the internal wall surface of the usual center cop tube 30 of the package 25 at its opposite end openings. 20

The lower flange 26 may be formed of sheet metal or of a moldable composition and is suitably affixed to the driving whorl 18, as by means of screws 31, whereby rotation of the driving whorl 18 by the band 19 will impart rotary motion 25 to the package 26 supported by the flange 26 and held in driving relation therewith by the prongs 28.

The upper flange 27 may be made of suitable material, such as metal, either in cast or in sheet 30 form, or of a composition moldable under heat and pressure, such as vulcanized hard rubber, vulcanized fibre, Bakelite or other common resinoid molding compositions.

The prongs 29 are struck out of a smaller disk 35 33 of sheet metal forming an insert fixed in the underside of the flange 27 and they extend downwardly to provide the wedging relationship with the cop tube 30 above mentioned.

Depending from the underside of the upper 40 flange 27 is a central tubular stud member 35 which is rigidly affixed at one end to the flange 27 by means of a reduced end portion 36 that projects through the central opening of the annular flange 27 and is suitably bent over its top 45 surface as indicated at 37, as by means of a peening operation. The stud 35 is provided with a bore 38 of a size for slidably receiving and telescopically retaining within the lower end portion of the stud the upper end portion 40 of the 50 spindle blade 17, as illustrated in Fig. 1.

Rising from the top surface of the flange 27 is the upstanding central hollow spindle member 41, the lower end portion of which is fixedly secured within the bore 38 of the stud 35, as by 55 having a forced-fit therein, while the upper free end portion of the spindle member 41 has slidably mounted thereon a demountable sleeve-like tip member or bullet 42. The bullet 42 has a pointed upper end portion 43 of frustro-conical 60 formation, and is made preferably of a material, such as aluminum or a moldable composition, such as Bakelite or other common resinoid compositions, capable of providing a smooth guiding edge over which the strand covering material 44 65 being withdrawn from the supply package 25 passes in being wrapped spirally around the elastic core 45 by means of the rotary action of the flier generally designated 46 during the upwardly advancing movement of the core 45 70 through the hollow spindles 10 and 41 during the covering operation.

The bullet 42 is formed with two intercommunicating bores 47 and 47' of different diameters, the smaller of which is at the upper end of 75

the bullet and has positioned therein a sleeve insert 48 composed of a hard wear-resisting material, such as a hardened steel bushing, suitably secured in place, as by having a pressed-fit within the bore. The bullet 42 may be of any desired length just so long as there is sufficient clearance between its bottom end face and the top of the flange 27 for the placing of one or more annular weights 49, such as metal washers, for weighting 10 the flier 46.

The flier 46 may be of any of the usual types and "per se" it forms no feature of the present invention. For example, one form of flier that may be used may comprise one having the form 15 disclosed and claimed in the copending design patent application of Henry B. Ahlberg, Serial No. D-87,530, filed October 6, 1939, in which the flier is of the form shown in Fig. 6 of the present drawings and has a sector-shaped body portion 20 50 formed of a piece of laminated fibrous material impregnated with a synthetic resin, and perforated as at 51 to provide a bearing for rotating on the tubular spindle member 41. A wire arm 52 has one end fixed as at 53 to the apex end 25 or neck portion of the body 50 and the arm extends radially outwardly therefrom and is coiled at its free end to provide a yarn-guide eye 55.

To detachably secure the tubular stud 35 to the spindle 40 and also to detachably hold the bullet 30 or tip member 42 to the tubular spindle member 41, we have provided a plurality of independent gripping means allowing the tip 42 and the stud 35 to be slid lengthwise on and off their respective spindles so as to facilitate the easy mounting 35 or removal of these parts whenever desired. For this purpose, there is provided on the spindle portion 40 a flat leaf spring 60 extending lengthwise of and housed in the longitudinal slot 61 in the outer side of the spindle blade portion 40 and held in place by suitable arcuate-shaped arms, as indicated at 62 in Fig. 1, which embrace the 40 lower end portion of the spindle blade section 40 and are positioned within the annular slot 63 formed in the exterior cylindrical surface of the 45 spindle portion 40 near its lower end. Thus, in the assembled relation of the upper flange 27 on the package 25, the tubular stud 35 will be telescoped over the spindle blade portion 40 to snugly fit the same and will be grippingly held to the 50 latter by means of friction created by the spring 60 pressing against the inside cylindrical wall surface of the tubular stud 35. Similarly, the sleeve-like tip member or bullet 42 is shown in Fig. 1 as being frictionally gripped internally 55 of the inner wall surface of its large bore 47 by a flat leaf spring 65 positioned in the longitudinal slot 66 on the tubular upright spindle member 41 and secured thereto by suitable arcuate arms, as indicated at 67 which embrace the exterior of 60 the upper end portion of the spindle 41 and are disposed in an annular slot 68 in proximity to its terminal end.

In order that one type and size of spindle blade 65 may be used in conjunction with various sizes of packages of covering material having different heights or axial dimensions, whenever it is desired to run either light, medium and heavy weight strand covering material on the same machine, and without the necessity for changing 70 the types of spindles as has heretofore been necessary with the prior art machines, a further feature of the invention contemplates the provision of an adapter device arranged within the package of covering material between the upper 75 demountable annular flange and the usual spindle

blade inside the package; and the adapter is so constructed and arranged as to connect and be relatively movable along the depending tubular stud member carried by the upper flange so as to properly center the upper flange and to bring the 5 bores of the two spindles into vertical alignment. Thus, in Fig. 2 there is shown one form of adapter comprising a sleeve member generally designated 70 of stepped formation having a bore 71 in its larger portion of a size to snugly fit within the 10 bore 38 of the depending tubular stud 35 of the demountable upper flange 27 and be retained in place by the gripping action of the leaf spring 74 housed in the longitudinal slot 75 in the stem 72 and secured thereto by the arcuate arms 76 which 15 are disposed in an embracing relation about the stem in a circular groove 78 near the free end of the stem. The bullet 42 and the hollow spindle member 41 on which it is carried, as shown in Fig. 2, have the same structure as that shown 20 in Fig. 1 and for specific details of such structure, reference is made to the description of these parts in connection with Fig. 1.

In Fig. 3 there is shown a modified form of adapter in which the upper flange 80 carries a 25 tubular stud member 81 the lower end portion of which is formed with a reduced externally 30 screw threaded portion 82 adapted to receive the internally screw threaded sleeve 83 which is slidably mounted by means of the central bore 84 upon 35 the driving spindle 40 and frictionally held thereto by the flat leaf spring 60. The sleeve 83 engages the top of the hub 85 on the spindle blade 17 and thus functions as a distance piece between the tubular stud 81 and the hub 85 of the spindle 35. 40 in the different adjusted positions of the sleeve for accommodating different heights of supply packages of the covering material. The sleeve 83 as thus arranged may be retracted or it may be extended to move relative to the tubular stud 81 45 as desired, by being turned by means of a wrench engaging the holes 86 and screwed either on or off the threaded portion 82 in the required direction so as to bring the lower portion of the sleeve well along the body of the spindle portion 40 or 50 into abutting relation with the top of the hub 85 when the upper flier supporting flange 27 is flush with the top end of the package 25. It will thus be apparent that a wide variety of adjusted positions may be obtained by adjustment of the 55 sleeve 83 in order to accommodate for the different heights or axial lengths of the various sized yarn packages 88 employed in the art and to enable the spindle blade portion 40 to correctly center the upper flange 80 when it is used with 55 different height packages of covering material.

In Fig. 3 there is also shown a different form of bullet 90 made either of aluminum or of a moldable resinoid material and having a frustro-conical upper end portion 91 and an enlarged flange 60 92 at its lower end for supporting the rotary flier 93 which is rotatably carried by the tubular body portion of the bullet. An annular ring 94 secured by a screw 95 to the tubular portion of the bullet well above the flier 93 serves to provide a stop 65 to limit the elevating movement of the flier as it revolves on the bullet during the covering operation. The bullet 90 is held to the upstanding central hollow spindle 96 carried by the flange 80, by a flat spring 97 and is easily removed by 70 75 sliding movement on and off the free end of the spindle 96.

In Fig. 5, there is illustrated another modified form of adapter structure for insuring correct alignment of the upstanding spindle 101 carried 75

by the upper flange 102 and supporting the frusto-conical sleeve-like tip member or bullet (not shown) and the rotatable flier 103, all of which being similar in structure to that illustrated in Figs. 1 and 2 with the exception of the depending stud 104 which in the present instance carries a flat spring 105 on the exterior of its lower end portion for frictionally engaging the inside wall surface of the adapter 106. The adapter 106 comprises a sleeve 100 having two inter-communicating bores 107 and 108 of different diameters, the smaller bore 108 being adapted to snugly fit and slidably receive the usual main spindle blade portion 40 of the spindle blade 10, while the larger bore 107 is of a size such as to slidably telescope over and receive the lower end portion of the depending tubular stud 104. When the parts are thus assembled, the sleeve 106 is held frictionally connected to the stud 104 and also to the spindle blade portion 40 by means of the leaf spring 105 and 40 respectively.

It will be apparent from the foregoing description that there has been disclosed several forms of coupling devices in accordance with the invention which permit application and use of the same flange and bullet supporting spindle member upon a plurality of different interchangeable yarn packages of different heights and thus there is provided a universal spindle arrangement whereby packages of different weights and kinds of covering material may be readily interchanged and substituted for each other on a common spindle.

The foregoing description is directed solely towards the constructions illustrated, but we desire it to be understood that we reserve the privilege of resorting to all the mechanical changes to which the device is susceptible.

We claim:

1. In combination, a rotatable spindle blade, a demountable sleeve-like tip member on said spindle arranged for longitudinal sliding movement on and off the same, and frictional gripping means between said spindle and said demountable member frictionally holding said tip member connected to said spindle for rotation in unison therewith in the assembled position of said elements.

2. In combination, a rotatable spindle blade, a demountable sleeve-like tip member on said spindle arranged for longitudinal sliding movement on and off the same, and resilient means between said spindle and said demountable member frictionally holding said tip member connected to said spindle for rotation in unison therewith in the assembled position of said elements.

3. In combination, a hollow rotatable spindle blade, a demountable sleeve-like member on said spindle arranged for longitudinal sliding movement on and off the same, and a spring disposed within said member between said spindle and said demountable member in their assembled position and frictionally enforcing a firm gripping relationship between said elements for holding said member connected to said spindle for rotation in unison.

4. In combination, a flange, a spindle member carried by said flange and extending upwardly from its top surface, a demountable tip member on said spindle arranged for longitudinal sliding movement on and off the free end portion of the same, and a leaf spring carried by one of said members having firm gripping engagement with the other of said members and located between the members in their assembled position for fric-

tionally holding said members connected together for rotation in unison.

5. In a spindle of the class described, a hollow rotatable spindle blade, upper and lower annular flange members to be rotated by said blade and between which flanges a hollow cylindrical package of strand covering material is to be detachably held, means detachably securing said package to said flanges when the package is positioned between the flanges, a sleeve member carried by said upper flange and depending from its underside, an adapter device demountably arranged upon the free end portion of said spindle blade for longitudinal sliding movement on and off the same, said adapter being so constructed and arranged as to receive and retain the lower end portion of said depending sleeve member and relative to which the adapter is longitudinally movable into different adjusted positions thereon, and frictional gripping means between said adapter and said spindle blade for detachably holding such elements connected together for rotation in unison.

6. In a spindle of the class described, a hollow rotatable spindle blade, upper and lower annular flange members to be rotated by said blade and between which flanges a hollow cylindrical package of strand covering material including a central cop tube is to be detachably held, means carried by each of said flange members insertable within the opposite end openings of the cop tube of said package and having gripping engagement with the inside wall surfaces of said tube for detachably securing said package to said flanges when the package is positioned between the flanges, a sleeve member carried by said upper flange and depending from its underside, an adapter device demountably arranged upon the free end portion of said spindle blade for longitudinal sliding movement on and off the same, said adapter being so constructed and arranged as to receive and retain the lower end portion of said depending sleeve member and relative to which the adapter is longitudinally movable into different adjusted positions thereon, and a leaf spring between said adapter and said spindle blade for detachably holding such elements connected together for rotation in unison.

7. In a spindle of the class described, a hollow rotatable spindle blade, upper and lower annular flange members to be rotated by said blade and between which flanges a hollow cylindrical package of strand covering material is to be detachably held, means detachably securing said package to said flanges when the package is positioned between the flanges, a sleeve member carried by said upper flange and depending from its underside, an adapter device demountably arranged upon the free end portion of said spindle blade for longitudinal sliding movement on and off the same, said adapter being so constructed and arranged as to receive and retain the lower end portion of said depending sleeve member and relative to which the adapter is longitudinally movable into different adjusted positions thereon, frictional gripping means between said adapter and said sleeve member detachably securing these members together, and frictional gripping means between said adapter and said spindle blade for detachably holding such elements connected together for rotation in unison.

8. In a spindle of the class described, a hollow rotatable spindle blade, upper and lower annular flange members to be rotated by said blade and between which flanges a hollow cylindrical pack-

age of strand covering material including a central cop tube is to be detachably held, means carried by each of said flange members insertable within the opposite end openings of the cop tube of said package and having gripping engagement with the inside wall surfaces of said tube for detachably securing said package to said flanges when the package is positioned between the flanges, a sleeve member carried by said upper flange and depending from its underside, an adapter device demountably arranged upon the free end portion of said spindle blade for longitudinal sliding movement on and off the same, said adapter being so constructed and arranged as to receive and retain the lower end portion of said depending sleeve member and relative to which the adapter is longitudinally movable into different adjusted positions thereon, a leaf spring between said adapter and said sleeve member detachably securing these members together, and a leaf spring between said adapter and said spindle blade for detachably holding such elements connected together for rotation in unison.

9. In a spindle of the class described, a hollow rotatable spindle blade, upper and lower annular flange members to be rotated by said blade and between which flanges a hollow cylindrical package of strand covering material is to be detachably held, means detachably securing said package to said flanges when the package is positioned between the flanges, a sleeve member carried by said upper flange and depending from its underside, an adapter device demountably arranged upon the free end portion of said spindle blade for longitudinal sliding movement on and off the same, said adapter having screw threaded connection with the lower end portion of said depending sleeve member and relative to which the adapter is adjustable to vary the effective length of the sleeve member upon relative rotation of the adapter thereon, and frictional gripping means between said adapter and said spindle blade for detachably holding said elements connected together for rotation in unison.

10. In a spindle of the class described, a hollow rotatable spindle blade, upper and lower annular flange members to be rotated by said blade and between which flanges a hollow cylindrical package of strand covering material is to be detachably held, means detachably securing said package to said flanges when the package is positioned between the flanges, a sleeve member carried by said upper flange and depending from its underside, an adapter device demountably arranged upon the free end portion of said spindle blade for longitudinal sliding movement on and off the same, said adapter having screw threaded connection with the lower end portion of said depending sleeve member and relative to which the adapter is adjustable to vary the effective length of the sleeve member upon relative rotation of the adapter thereon, and a leaf spring between said adapter and said spindle blade for

detachably holding said elements connected together for rotation in unison.

11. In a spindle of the class described, a hollow rotatable spindle blade, upper and lower annular flange members to be rotated by said blade and between which flanges a hollow cylindrical package of strand covering material is to be detachably held, means detachably securing said package to said flanges when the package is positioned between the flanges, a hollow spindle member carried by said upper flange and extending upwardly from its top surface, a demountable tip member on said last named spindle member, frictional gripping means between said spindle member and said tip member for detachably securing said members together for rotation in unison, a sleeve member carried by said upper flange and depending from its underside, an adapter device demountably arranged upon the free end portion of said spindle blade for longitudinal sliding movement on and off the same, said adapter being so constructed and arranged as to receive and retain the lower end portion of said depending sleeve member and relative to which the adapter is longitudinally movable into different adjusted positions thereon, and frictional gripping means between said adapter and said spindle blade for detachably holding such elements connected together for rotation in unison.

12. In a spindle of the class described, a hollow rotatable spindle blade, upper and lower annular flange members to be rotated by said blade and between which flanges a hollow cylindrical package of strand covering material including a central cop tube is to be detachably held, means carried by each of said flange members insertable within the opposite end opening of the cop tube of said package and having gripping engagement with the inside wall surfaces of said tube for detachably securing said package to said flanges when the package is positioned between the flanges, a hollow spindle member carried by said upper flange and extending upwardly from its top surface, a demountable tip member on said last named spindle member, a leaf spring carried by and located between said spindle member and said tip member for detachably securing said members together for rotation in unison, a sleeve member carried by said upper flange and depending from its underside, an adapter device demountably arranged upon the free end portion of said spindle blade for longitudinal sliding movement on and off the same, said adapter being so constructed and arranged as to receive and retain the lower end portion of said depending sleeve member and relative to which the adapter is longitudinally movable into different adjusted positions thereon, and a leaf spring between said adapter and said spindle blade for detachably holding such elements connected together for rotation in unison.
